UNITED STATES PATENT OFFICE.

FELIX J. RUSH, OF NEW YORK, N. Y.

ELECTRIC TRIMMING APPARATUS.

No. 844,406.

Specification of Letters Patent.

Patented Feb. 19, 1907.

Application filed September 16, 1905. Serial No. 278,725.

To all whom it may concern:

Be it known that I, FELIX J. RUSH, a citizen of the United States of America, and a resident of the borough of Manhattan, in the city, county, and State of New York, have invented certain new and useful Improvements in Electric Trimming Apparatus, of which the following is a specification.

This invention relates to apparatus or devices for trimming fabrics of various kinds, and particularly to a device or apparatus by means of which fabrics may be trimmed along the outline of any given pattern or the surfaces of pile or similar fabrics may be trimmed and rendered even and uniform.

Among the objects of my invention the following may be noted: to provide a simple and compact device by means of which embroidery of any character whatsoever may have the foundation fabric upon which it is made or laid accurately and perfectly trimmed close to and along its outline, to provide means by which the surfaces of pile or other similar fabrics may be trimmed or worked down so as to render said fabrics of uniform thickness throughout and give to the said surfaces an even and uniform appearance, to provide a device which will trim all kinds of fabric by means of singeing in contradistinction to cutting, and to provide a device by means of which the above objects may be effectively carried out which is under the perfect control of the operator and which may be manipulated with ease and freedom for the various purposes stated.

With the above objects in view and others which will be detailed during the course of this description my invention consists in the parts, features, and combinations of elements hereinafter described and claimed.

In the drawings forming part of this specification, Figure 1 is a side elevation of a form of device which I have devised for the purpose of demonstrating my invention, certain parts of said figure being shown in section in order to clearly portray the details of construction; and Fig. 2 is a bottom plan view of Fig. 1.

Referring now to Fig. 1 of the drawings, my device, in the form shown, consists of the central supporting stem or shaft *a*, which is preferably made of copper, but may be made of any other material which is a good conductor of electricity, said stem or shaft carrying a slip-ring *a'*, which in this instance is made solid and with an extensive bearing-

surface, as shown. The stem *a* below the slip-ring *a'* is provided with a shoulder *a²*, below which is an insulating-sleeve *b*, the upper end of which is flanged at *b³* and which sleeve is clamped against the shoulder *a²* by means of the nut *a³*, working upon the screw-threaded portion *a⁴* of the stem provided for the purpose, a washer *a⁴*, of mica or other insulating material, being interposed between the said sleeve *b* and the nut *a³*. Coöperating with the flange *b³* of the insulating-sleeve *b* is a second slip-ring *b'*, the same surrounding said sleeve *b* and being held against its flange by any suitable means, the insulating-washer *a⁴* being made sufficiently extensive to overlap the lower end of said slip-ring, and thus insulate the same from the nut *a³* and also act as a support for said slip-ring. At the lower end of the stem *a* a suitable head or block *c* is secured, the said stem being screw-threaded into the said block, as shown, for the purpose. Obviously any other means for the purpose may be employed provided an electric connection be established. Said head or block supports a binding-post *d* by means of the reduced lower end *d²* thereof being set within an aperture in the said block or head, said reduced end *d²* being surrounded by an insulating-sleeve *c²*, the upper end of which is flanged at *c³* and the lower end of which rests upon the insulating-washer *d⁴*, interposed between the bottom of the block or head *c* and a scouring-nut *d³*, screwed upon the lower end of the binding-post *d*. This construction firmly secures the binding-post in position and insulates the same from the head or block *c*.

The binding-post *d* is bored transversely for the reception of one end of the conducting-wire *b²*, which at its other end is tapped into the slip-ring *b'* and intermediately bent around the stem *a'*, so as to avoid contact therewith. The screw *b³* secures the said conductor *b²* in the binding-post. This establishes an electric connection between the slip-ring *b'* and the binding-post *d*, the current through which, however, is insulated from the stem *a* and its head *c*.

Secured to the head or block *c* are a plurality of wires, preferably shown as four and three of which are indicated by *c'* and the other one by *d'*. The wires *c'* are connected at their upper ends directly to the block or head *c* by means of the binding-screws *c²*, which are tapped into said head and firmly hold the upper ends of said wires in apertures

made in said head or block for their reception. The wire d' passes into a longitudinal bore in the binding-post d and is securely held therein by means of the screw d^5 , tapped through the binding-post into engagement with said wire. The several wires c' and d' are joined at their lower ends and secured together in any suitable manner, said ends being subsequently formed into an elongated piercing-point d^x for a purpose presently stated. The wire d' is the trimming or singeing wire and is preferably made of platinum or other poor conductor of the electric current, while the other wires c' are or may be made of bronze or other material which is a good conductor of the electric current. The wires c' and d' are arranged so that the wires c' will extend substantially straight from the head or block c to the point d^x , while the wire d' is slightly bowed or bent inwardly between its ends. In this manner the wires c' act as guards to prevent the wire d' getting too close to the edge or surface which is to be trimmed or treated. In other words, it is an important feature of my invention that the radius of operation of the wires c' shall be slightly greater than the radius of operation of the wire d' , for the wire d' being a poor conductor, and consequently having high resistance, will attain to a considerable degree of heat, while the wires c' being good conductors and having low resistance will readily pass the current and will thus not become overheated. For the purposes of my invention a sufficient current of low voltage will bring the wire d' to red heat, thus causing it to expand or elongate, which might, if the wire were straight, cause it to bow outwardly beyond the radius of action of the guard-wires c' , and to avoid this the initial bend inwardly is given the wire d' , so that its natural tendency to elongate or expand when heated will cause it to bow still more inwardly. This inward bend is intended to be slight or only sufficient to enable the heat radiated thereby to substantially reach the extreme of radius of action of the guard-wires c' , thus the singeing or trimming effect of the wire will be caused to reach substantially the radius of action of the said guard-wires. In the description of operation of the device these features will be clearly stated and their functions amplified. In order to transmit the current and complete the circuit, a brush h is placed so as to contact and coöperate with the slip-ring a' , and a brush h' is likewise brought into coöperation with the slip-ring b' , a conducting-lead h^2 being connected to the brush h and a conducting-lead h^3 being connected to the brush h' . A guard and handhold f surrounds the entire device, the latter being loosely mounted thereon, so as to freely rotate by means of the flanged ring f' , secured to the top of the guard and engaging the flanged sleeve g , which surrounds and

is secured to the stem a , said ring and sleeve being insulated by means of the interposed insulating material g^2 and at its bottom is supported by means of the flanged ring f^2 , which coöperates with the supporting-ring g^2 , secured to the head or block c by the binding-screws c^2 , said supporting-ring g^2 being insulated from the said head c by means of the interposed insulating material g^3 , which is also carried out to surround the screws c^2 . By this means the entire device is journaled in and rotates on the guard f , and as the latter is insulated from said device it may be freely handled. Obviously the brushes h and h' are held stationary by suitably connecting the same with the handhold or guard f and are suitably insulated from the latter, or the latter may be made of non-conducting material. The said brushes through their leads h^2 and h^3 are obviously connected to any suitable source of electric current, which may be controlled by any suitable form of rheostat interposed in the circuit for permitting just the desired current and voltage to pass to the wires c' and d' for the given purposes.

Having described the details of my invention, the following description of the mode of operation will be readily understood: The stem or shaft a will be held and supported by a chuck or other device connected to and driven by a flexible shaft which may be given any desired speed of rotation, the said shaft or stem, as before stated, being journaled in the guard f . Rotary motion being thus imparted to the device and the electric circuit having been closed, the current will be transmitted through the lead h^3 , brush h' , slip-ring b' , conductor b^2 , and binding-post d to the singeing-wire d' , the current passing along the latter to its juncture with the guard-wires c' , where it will be divided and pass along the several conductors or guard-wires c' to the head or block c , and thence to the stem a , and through the slip-ring a' to the brush h , and thence to the return-lead h^2 . We now have the implement under rapid rotation and with the current passing therethrough, and shortly the wire d' will reach a glow and will be in condition for performing its functions. Assuming now, for example, that a pattern in embroidery thread or braid has been produced upon a foundation fabric and that it is desired to trim away the foundation fabric close to, along, and around the pattern, so as to leave the latter in clear-cut outline, the piercing-point d^x will first be entered through the foundation fabric at any point it is desired. This will bring the heated singeing-wire d' into engagement with said foundation fabric, which latter will be instantly singed and charred away, the operator then bringing the instrument close to the edge of the embroidery for the purpose of removing the foundation fabric close

thereto. As previously stated, the wires c' , of which there are preferably three and which are arranged in triangular relation, constitute a guard and perform their functions as 5 guards by reason of the fact that in the rapid rotation of the instrument they become practically a solid or continuous surface which presents itself against the embroidery or pattern on the foundation material and uses said embroidery or pattern as a guide-wall—that is to say, the embroidery made into a pattern is necessarily stiffer, and very much more so, than the foundation material, and in consequence presents a considerable resistance to pressure 10 thereon by the instrument in its operation. Therefore as the operator approaches the instrument to the embroidery the singeing-wire will remove the foundation material, and the guard-wires, operating as described, will engage the embroidery edge and prevent the singeing-wire from having any effect thereon. If undue pressure of the instrument is brought to bear upon the edge of the embroidery, the latter will necessarily give way, thus preventing 15 the singeing-wire from affecting the same. Moreover, as previously stated, by bowing the wire inwardly, as described, and by reason of its elongation and increased bowing under heat and rotation, the singeing-wire 20 as well as the radius of action of the heat radiated thereby will be kept within bounds and prevented from operating beyond the radius of action of the guard-wires. In consequence no injury can result to the embroidery, 25 though the foundation fabric, which is comparatively light, will necessarily be trimmed or singed and charred away. Obviously the entire length of the singeing-wire can be utilized and the degree of rapidity 30 of its singeing action may be controlled by reason of the converging arrangement of the same and the guard-wires, and it will be readily understood that if the foundation material is to be removed from a small circle 35 of embroidery it is only necessary to enter the point into the fabric until the extreme lower end of the guard-wires reach the same, whereupon a rapid movement of the instrument will completely remove the said foundation 40 fabric within the circle, and after the fabric has been pierced or penetrated by the point d^x it is clear that the instrument may be entered thereinto as deeply as desired, whereby to remove the foundation fabric as 45 rapidly as the operator wishes, the embroidery-pattern acting as a guide to facilitate the trimming. Thus an important feature of the invention resides in providing the piercing-point d^x to penetrate the foundation 50 fabric in order to bring the singeing-wire d' into action and additionally to control its singeing action. As previously stated, the singeing-wire is composed of a material of 55 high resistance and low conductivity, while the guard-wires are composed of a material

of low resistance and high conductivity, and by reason of there being several guard-wires of high conductivity the current passing through the singeing-wire will be divided at the point of juncture of said wires and will 70 pass equally along the said guard-wires through the instrument on the return-lead. This arrangement is important in that it prevents the current translated by the singeing-wire d' from objectionably heating the 75 point d^x or the guard-wires c' . In fact, by the arrangement of the guard-wires and their composition the possibility of the same becoming overheated is completely eliminated, and stress is laid upon this feature of 80 my invention, as it is quite important. By providing the rheostat the degree of current transmitted to the singeing-wire can be regulated to a nicety and undue heating of said wire is thereby prevented. 85

Too much stress cannot be laid upon the function and operation of the guard-wires c' in respect of their function of acting as a guard to the embroidery and preventing the singeing-wire from acting thereon and removing therefrom the immediate foundation thereof, as well as in their aspect of operating as a brace to prevent the possibility of the operator's hand carrying the singeing-wire 90 too far over against the embroidery edge in 95 following the outline of the pattern. Another important function of the guard-wires is to clean or sweep the edge of the embroidery or pattern as the singeing or trimming takes place—that is to say, as the foundation fabric is singed or charred away an ash or fluff may remain on or cling to the edge or surface being treated, and such ash or fluff will be effectively removed and the said edge or surface thoroughly cleaned by 100 the action of the rapidly-rotating guard-wires. Moreover, these guard-wires have the same function when the implement is carried across the surface of a pile or nap fabric the surface of which it is desired to render uniform, the guards also acting to prevent the implement from being carried too close to the body material. Obviously the 105 rapidity of rotation of the instrument may be regulated by any suitable means. 110 115

It should be distinctly understood as an important part of my invention that neither the guard-wires c' nor the point d^x becomes unduly heated and that said point is essentially a piercing-point, the function of which 120 is simply to penetrate the work. In operating upon the surface of a fabric or upon a free edge thereof the piercing-point will have no function.

Having thus described my invention, what 125 I claim, and desire to secure by Letters Patent, is—

1. An electric trimming apparatus having in combination a conducting filament, means for supporting said filament by its ends so as 130

to leave it free and unsupported between its ends, a guard coöperating with the free portion of said filament and means for translating an electric current to and through said filament, whereby the latter may be heated 5 for singeing purposes.

2. An electric trimming apparatus having in combination a holder, a conducting filament, a guard, and means for translating an 10 electric current to and through said filament, the latter being supported at one end by the holder and at the other end by the guard, whereby said filament is exposed between its ends to present singeing portions.

3. An electric trimming apparatus comprising a singeing filament capable of being heated by the passage therethrough of an electric current; a holder for said filament; means for rotating said holder; and leads in 20 electric connection with portions of the singeing filament, the latter being extended beyond said holder and having a portion thereof exposed between its ends for contact with work to be trimmed.

4. An electric trimming apparatus comprising a singeing filament capable of being heated by the passage therethrough of an electric current, said filament being extended beyond its singeing portion to form a 30 piercing-point; a holder for said filament; and leads in electric connection with portions of said filament, the latter being extended beyond said holder and having a portion thereof exposed between its ends for contact with work to be trimmed.

5. An electric trimming apparatus comprising a singeing filament capable of being heated by the passage therethrough of an electric current; a holder for said filament; 40 leads in electric connection with portions of the singeing filament, the latter being extended beyond said holder and having a portion thereof exposed between its ends for contact with work to be trimmed; and a 45 guard coöperating with said filament and connected therewith so as to aid in its support.

6. An electric trimming apparatus, having in combination a support, a trimming device 50 carried thereby, said trimming device being provided with a piercing-point, a guard partially surrounding said trimming device and means whereby an electric current may be translated to and through said trimming device.

7. An electric trimming apparatus having in combination a support, a trimming device carried thereby, said trimming device being provided with a piercing-point, a guard co- 60 operating with said trimming device, and means for translating an electric current to and through said trimming device for heating the latter without proportionately heating its piercing-point.

8. An electric trimming apparatus having

in combination a support, a trimming device carried thereby, said trimming device being provided with a piercing-point, a guard coöperating with said trimming device, a hand-hold surrounding said support and by which the latter is carried, and means for translating an electric current to and through said trimming device.

9. An electric trimming apparatus having in combination a rotary shaft, a trimming 75 device carried thereby, a guard coöperating with said trimming device, and means for translating an electric current to and through said trimming device.

10. An electric trimming apparatus having 80 in combination a support, a trimming device carried thereby, a guard coöperating with said trimming device, means whereby an electric current may be translated to and through said trimming device, and means for 85 regulating the current translated to said trimming device.

11. An electric trimming apparatus having in combination a rotary shaft, a trimming device carried thereby, a flexible driving 90 means connected to said shaft, whereby the apparatus may be manipulated as desired, and an electric circuit for translating a current to and through the said trimming device.

12. An electric trimming apparatus having in combination a rotary shaft, a combined trimming device and guard carried by said shaft, the guard being divided into a plurality of parts, and the said parts and the said 100 trimming device being caused to converge and being combined and formed into a piercing-point, and means whereby an electric current may be translated to and through the trimming device.

13. An electric trimming apparatus having in combination a rotary shaft, a combined guard and trimming device carried by said shaft, means for translating an electric current to and through said trimming device and guard, and a piercing-point formed in prolongation of the said guard and trimming device, said guard and trimming device being composed of a plurality of wires disposed in substantially conical form, and the trimming-wire being bowed slightly relatively to the guard-wires.

14. An electric trimming apparatus having in combination a rotary shaft, a plurality of slip-rings carried thereby, and a head secured 120 to the end thereof, a combined trimming device and guard composed of a plurality of wires each connected to said head, said wires being combined at one end and prolonged into a piercing-point, means whereby an 125 electric current may be translated to one of the slip-rings and thence to the trimming-wire and passing through the latter and the guard-wires, thence to and through the said shaft and to the other of the slip-rings, and 130

thence to the return-lead, and a handhold or guard surrounding said apparatus whereby the same may be manipulated at will.

15. An electric trimming apparatus having in combination a rotary shaft, two slip-rings carried thereby, and a head supported on the end thereof, a combined guard and trimming device carried by said head, said guard and trimming device being joined and formed 10 into a piercing-point, a handhold or guard surrounding said apparatus, and means for translating an electric current to and through the trimming device comprising the stationary brushes carried by the handhold or 15 guard and bearing respectively upon the slip-rings, a lead connecting one of the slip-rings with the trimming device, and means electrically connecting the guard with the rotary shaft to which latter the other slip-ring is electrically connected, substantially as 20 described.

16. An electric trimming apparatus having in combination a holder, a conducting fila-

ment having a piercing-point, means for translating an electric current to and through 25 said filament, and means coöperating with the point of said filament to prevent the current overheating and to maintain the same at a lower temperature than the body of the filament.

17. An electric trimming apparatus having in combination a holder, a trimming-wire, a guard composed of a plurality of wires, and means for translating an electric current to and through said trimming and guard wires, 30 35 said trimming wire being composed of a metal of higher resistance than the guard-wires whereby the latter remain comparatively cool.

Signed at New York this 11th day of September, 1905.
